UNITED STATES PATENT OFFICE.

MATTHEW A. FORD, OF DAVENPORT, IOWA.

LUGGAGE CARRIER.

1,407,994.

Specification of Letters Patent. Patented Feb. 28, 1922.

Application filed December 8, 1920. Serial No. 429,193.

To all whom it may concern:

Be it known that I, MATTHEW A. FORD, a citizen of the United States, residing at Davenport, in the county of Scott and State 5 of Iowa, have invented certain new and useful Improvements in Luggage Carriers, of which the following is a specification.

This invention relates in general to luggage carriers, and has more particular reference to a device for holding luggage of 10 various descriptions in position on the running board of an automobile.

One of the primary objects of the present invention is to provide a luggage carrier of 15 novel construction, adapted for attachment to the running board of any automobile, and which is so constructed that it may be quickly and easily transformed from operative to inoperative condition, that is, from a luggage-carrying to a collapsed condition. In 20 the latter condition, the carrier parts are in very compact relation, occupying but a small space along the edge of the running board.

Another object is to provide a luggage carrier of the character described, which will 25 comprise such few parts of simple construction as to enable production of the article at a comparatively low cost.

I have also aimed to provide a luggage 30 carrier especially adapted to be attached to the brackets which support the running board, thus utilizing the same bolts employed for connecting the running board to its brackets. It follows, therefore, that the 35 use of extra bolts, screws, clamps or other extraneous fastening devices is dispensed with.

Still another object is to provide a novel 40 means for supporting the luggage-retaining bars or members in operative position and permitting them to be quickly and easily collapsed or moved to an inoperative position in which they are retained against rattling by means including the bar-supporting 45 means.

Figure 1 is a side elevation of a luggage 50 carrier embodying my invention in operative condition, attached to the running board of an automobile.

Fig. 2, a plan view of the carrier in the 55 position shown in Fig. 1;

Fig. 3, a side elevation of the luggage carrier in collapsed inoperative condition;

Fig. 4, a detail top view of the main channel bar used in the carrier; and

Figs. 5, 6 and 7, sectional views taken on

the lines 5—5, 6—6 and 7—7, of Figs. 1, 3 and 2, respectively.

My invention contemplates, generally stated, the provision of a frame member 60 adapted to be rigidly attached to the running board or to any other part of an automobile, or any other vehicle or body on which luggage of various descriptions might be carried, a plurality of luggage-retaining bars and a 65 pair of longitudinally tapered bars adjustably mounted on the frame member for supporting the luggage-retaining bars in operative position, and movable to an inoperative position and adapted to be clamped therein 70 for holding the luggage-retaining bars in a collapsed or closely associated relation.

In the present illustration of one practical embodiment of my invention, the main frame member is in the form of a channel 75 bar 8 adapted to be rigidly supported at the outer edge of a running board 9 or attached to any suitable support by any suitable means, such for example as a pair of brackets 11 in the form of channel iron bars. The 80 bars 8 and 11 are adjustably connected by bolts 12, the latter of which pass through slots 13 in the bar 8, so as to permit of suitable spacing of the bars 11 to accommodate them to the channel brackets 20, which support the running board. As shown in Figs. 85 2 and 7, the brackets 11 fit within the channels of the brackets 20, so that the same bolts 14 which connect the running board to its brackets may be employed for attaching the 90 brackets 11 to the brackets 20. The main channel bar 8 is also formed with two T-shaped slots 15, through each enlarged end of which is adapted to be passed an upright 95 supporting bar of sectional construction, comprising the sections 16 and 17 pivotally connected together at 18. Each sectional part 16 has a reduced threaded shank 19, on which is loosely positioned a hooked latch member 21 and a wing nut 22. When the 100 upright supporting members are positioned with their shanks 19 in the smaller ends of the slots 15, it may be rigidly secured to the channel bar 8 by tightening the wing nuts, as shown in Figs. 1 and 5. The sectional 105 supporting members 17 have riveted to their outer ends a luggage-retaining bar 23. A pair of similar bars 24 are adapted to be supported in vertically spaced relation upon and by the sectional supporting members 110 16. Each member 16 is tapered longitudinally, as shown in Fig. 5, and the bars 24

are held in position by the action of the tapered ends of the bars 24 against the shanks 19 of the sections 16.

have apertures of different sizes for the reception of the bars 16, limiting the position of the bars 24 on said bars 16. The bars 23 and 24 are preferably shaped or equipped 5 with inwardly projecting luggage-retaining ends, preferably in the form of end members 25 pivotally connected at 26 to the bars so that the end members may be swung substantially into alignment with their respective bars when the carrier parts are moved 10 to collapsed position. It should be understood that my invention is in no way limited to the number and dimensions of the luggage-retaining bars, as these may be constructed to suit the needs of any particular 15 type of luggage carrier. The description thus far completes the luggage carrier in its operative condition, it being particularly noted that all of the parts are held in rigid 20 relative relation with the exception of the bars 24 which are free to be raised on the vertical bars 16, but which gravitate to the lowermost position permitted by their respective apertures and the taper of the bars 25 16. The bars 24 become, in fact, wedged to a certain degree on the tapered bars 16 so as to preclude rattling.

When the luggage carrier is not in use, it 30 may be packed away, or rather collapsed, into a very compact bundle without detaching it from its position on the running board. This is effected by loosening the wing nuts 22, folding the retaining ends 25 against the bars 23 and 24, shifting the bars 35 16 laterally, in the present instance to the right, until they are disposed in alignment with the larger ends of the slots 15, and then passing the rod 16 downwardly through said slots as far as possible, that is, 40 until the bars 23 and 24 rest one upon the other on the main channel bar 8, as shown in Fig. 2. In this position, it will be observed that the pivotal connections 18 are disposed substantially below the channel 45 bar 8. The bars 16 may then be swung upwardly toward each other so that each bears upon the adjacent channel bracket 11 as a fulcrum. The hooked members 21 are then 50 swung upwardly and engaged over the top of the bar 23, so as to clamp and retain the several parts in collapsed relation, as shown in Figs. 3 and 6. In this position, the members 16 act as a lever fulcrumed on the 55 channel brackets 11 for drawing the outer ends of the bar 23 tightly upon the main channel bar 8 and the interposed bars 24, and the hooked members 21 are so shaped and proportioned as to snap over the top 60 bar 23, placing the latter and the bars 24 at their medial portions under sufficient tension to insure holding the several parts in position without rattling. It will be observed that in this position the wing nuts 65 will not become loose and be lost, because they are prevented from turning by reason

of the fact that the wings strike the channel bar 8 and prevent the nuts from turning. To place the luggage carrier in operative condition again, the hooked latch members 21 are loosened by pressing upwardly on the inner ends of the bar 16, which when loosened, drop to a vertical position. The top bar 23 may then be raised to the highest elevation permitted by the wing nuts 22, whereupon the bars 16 will be shifted to the left so that their wings 19 enter the smaller 70 ends of the slots 15. The wing nuts will be tightened in this position, thereby rigidly 75 securing the several parts in operative condition. The intermediate horizontal bars 24 80 gravitate to their proper positions.

Attention is particularly directed to the method of attaching the luggage carrier in operative relation to the running board. By connecting the brackets 11 directly to the running board brackets 20 by the same bolts which connect the latter and the running board or by any other standard equipment bolts, such as fender bolts, I obtain a very rigid and durable fastening and support for 90 the luggage carrier involving but a minimum number of parts. The luggage channels fit in the running board channel brackets and are thus firmly held as against lateral displacement. By making the 95 brackets 11 adjustable lengthwise of and upon the channel bar 8, the luggage carrier may be attached to any automobile of standard construction.

It is believed that the foregoing conveys 100 a clear understanding of the objects prefaced above, and while I have illustrated and described but a single working embodiment of my invention, it should be understood that various changes might be made in details 105 of construction and in the size, proportion and number of parts without departing from the spirit and scope of the invention as expressed in the appended claims, in which—

I claim:

1. A luggage carrier for automobiles adapted to be attached to a running board thereof, comprising a plurality of horizontal luggage retaining members adapted to be supported one above the other in spaced 115 operative relation at the outer edge of the running board, and means attached only to the underside of the running board for supporting said members in said operative position, said members and their supporting 120 members being so constructed that the horizontal members may be positioned one upon another in compact collapsible relation beyond the outer edge and beneath the top of the running board and held in such collapsed 125 relation by said supporting means.

2. A luggage carrier comprising a plurality of luggage-retaining bars, a pair of longitudinally tapered members the tapered surfaces of which support said bars in ver- 130

- tically spaced relation, certain of said bars being slidable on said members into compact relation, means carrying said members and adapted for attachment to a suitable support, said members being movable relatively to said means to bring the luggage-retaining bars into compact relation, and means for locking the several parts in said compact relation.
- 10 3. A luggage carrier comprising a plurality of luggage-retaining bars, a frame member adapted for attachment to a suitable support, and longitudinally tapered members the tapered surfaces of which are adapted for supporting said bars on said frame member in spaced relation, said members being movable relatively to the frame member for bringing the bars into compact relation with said frame member.
- 20 4. A luggage carrier comprising a plurality of luggage retaining bars, a frame member adapted for attachment to a suitable support, longitudinally tapered members for supporting said bars on said frame member in spaced relation and movable relatively to the frame member for bringing the bars into compact relation with said frame member, and end retaining members pivotally mounted on the ends of said luggage-retaining bars and movable from a position at substantially right angles thereto into one substantially in alignment therewith.
- 30 5. A luggage carrier comprising a channel bar having a pair of T slots therein, means for attaching the channel bar to a suitable supporting body, a pair of longitudinally tapered members each movable lengthwise through the larger end of one of said slots and adapted to be secured in operative position in the smaller end thereof, a plurality of luggage-retaining bars supported on said tapered bars, and a member carried by each bar for locking the luggage-retaining member in connection with the channel bar when the parts are in compact relation.
- 40 6. A luggage carrier comprising a channel bar, a pair of brackets for connecting the bar to a suitable support and adjustable lengthwise on the bar, a plurality of horizontal luggage-retaining bars, means supporting said luggage bars in vertically spaced relation upon and above the channel bar, said means permitting the luggage-retaining bars to be lowered one upon another into compact relation on the channel bar, and means for locking the parts in such compact relation.
- 50 7. A luggage carrier for automobiles adapted for attachment to a running board thereof, comprising a pair of vertical supporting members, means for adjustably attaching them to the running board at the outer edge thereof, and a plurality of horizontal luggage retaining bars vertically
- slidable upon said vertical members from spaced operative relation thereon to a compact position beneath the top of the running board, said supporting members being movable from said vertical position to a horizontal position.
- 60 8. A luggage carrier comprising a supporting frame, a plurality of luggage-retaining bars, upright supporting members vertically slidable through the frame to operative and inoperative positions in which to hold the luggage retaining bars in vertically spaced and compact relation respectively, and means for locking said supporting members to said frame in either operative or inoperative position.
- 70 9. A luggage carrier comprising a frame member, a plurality of luggage-retaining bars, a pair of supporting members movably associated with the frame member for holding the luggage-retaining bars either in operative vertically spaced or inoperative compact relation, and each equipped with a wing nut adapted to be tightened for locking the supporting member in operative position, said supporting members being so disposed when in inoperative position that the wing nuts are precluded from turning.
- 80 10. A luggage carrier comprising a frame member, a plurality of luggage-retaining bars, a pair of supporting members each comprising pivotally connected parts, one of the luggage-retaining bars being rigidly connected to one pair of said pivotally connected parts, the other pair of pivotally connected parts being longitudinally tapered, the remaining luggage-retaining bars being slidable upon said tapered parts and held thereby in vertically spaced relation, and means whereby said supporting members may be moved relatively to the frame member for moving the luggage-retaining bars to operative and inoperative positions.
- 90 11. A luggage carrier for automobiles comprising a pair of horizontal brackets adapted to be rigidly attached to the underside of one of the running boards with the outer ends of the brackets extending beyond said board, a frame member mounted on said extended ends of said brackets, the connection between said member and brackets permitting adjustment of the latter toward and from each other to accommodate them to standard bolt connections on the underside of the running board, and luggage retaining means mounted on said frame member.
- 100 12. A luggage carrier for automobiles comprising a luggage-retaining structure, and means for attaching said structure to the underside of a running board to standard bolt connections thereon, said means comprising members constructed to receive said bolts and be rigidly secured thereby to the running board, said members being adjustable toward and from each other upon
- 110 130

and with respect to the carrier proper whereby to align said members with the standard bolt connections of different automobiles.

- 5 13. A luggage carrier for automobiles adapted for attachment to a running board by means of standard bolt connections thereto, comprising a luggage carrier proper adapted to be supported along the outer 10 edge of the running board, a pair of supporting members for the luggage carrier adjustable toward and from each other upon and with respect to the luggage carrier proper for alignment with said standard 15 bolt connections on different automobiles.
14. A luggage carrier for automobiles adapted to be supported along the outer edge of a running board, comprising in combination with standard bolt connections on 20 the underside of the running board, of a luggage carrier having longitudinally spaced

members reaching under the running board and rigidly attached by said bolt connections thereto, said luggage carrier being constructed to permit adjustment of said members 25 toward and from each other longitudinally of the running board into alignment with said standard bolt connections of different automobiles.

15. A luggage carrier for automobiles 30 adapted to be supported along the outer edge of a running board thereof comprising a plurality of horizontal luggage retaining bars, of means for supporting said bars in vertically spaced operative relation along 35 the outer edge of said running board, comprising longitudinally tapered upright members upon and by the tapered surfaces of which said bars are supported in vertically spaced relation.

MATTHEW A. FORD.
